(57) **CLAIM**

The ornamental design for a water wheel, as shown and described.

DESCRIPTION

FIG. 1 is a rear isometric view of my ornamental water wheel design;

FIG. 2 is a front isometric view of my design shown in FIG. 1;

FIG. 3 is a side view of my design shown in FIG. 1 with the opposite side being substantially a mirror image thereof; FIG. 4 is a rear view of my design shown in FIG. 1; FIG. 5 is a front view of my design shown in FIG. 1; FIG. 6 is a top view of my design shown in FIG. 1; and, FIG. 7 is a bottom view of my design shown in FIG. 1.

The foregoing FIGS. 1–7 consist of photographs of the subject design. These photographs are not intended to indicate any explicit colors associated with the design. In addition, in some of the photographs, certain items are depicted in the background. Such items, such as shadows and backdrop, are not part of the subject design and are therefore disclaimed. Furthermore, the text description which appears in some of the photographs is disclaimed.
